REGULATING SYSTEM

Franklin L. Snyder, Sharon, Pa., assignor to
Westinghouse Electric & Manufacturing Com-
pany, East Pittsburgh, Pa., a corporation of
Pennsylvania

Application March 23, 1935, Serial No. 12,549

9 Claims. (Cl. 171—119)

My invention relates to apparatus for adjusting the voltage of an alternating-current circuit and it has particular relation to regulating equipment capable of automatically effecting such adjustment in a small number of steps when the voltage or other characteristic of the circuit deviates sufficiently from a desired value to require correction.

In present-day electrical distribution systems, it is customary to supply energy to distant points of consumption through relatively long feeder circuits. As the loading of such a circuit increases, the voltage drop through its impedance is similarly raised with the result that the receiving end voltage is much lower for heavy than for light values of loading. In many instances, the nature of the load supplied is such that the resulting wide variation in voltage is, while of course undesirable, not objectionable to the point that further expenditure for feeder circuit regulators of the induction and other relatively expensive types is justified. My invention is directed to an improved type of automatic voltage adjuster which, because of its low cost and extreme simplicity, can be practically applied in situations of the above-outlined type.

One object of my invention is to reduce the cost of equipment adapted to automatically adjust in one or two steps the voltage of an alternating-current circuit.

Another object of my invention is to provide an improved control system for such adjusting equipments.

A further object is to increase the reliability and reduce the frequency of operation of the equipments of the type under consideration.

In practicing my invention, I associate with the circuit to be regulated, an auto or other transformer having a continuously energized primary winding and a two-section secondary winding which is capable of carrying the circuit load current. This secondary winding is arranged to be partially or wholly connected in series with one of the circuit conductors upon the actuation of control apparatus responsive either to changes in the circuit voltage or in the load current. To effect the described connection control without interrupting the regulated circuit load current, I utilize an especially designed magnetically-operated tap changer which determines the portion of the secondary winding in active circuit connection. The new equipment may be designed to effect either a one or a two-step voltage adjustment.

My invention itself, together with additional

objects and advantages thereof, will best be understood through the following description of specific embodiments when taken in conjunction with the accompanying drawing, in which:

Figure 1 is a diagrammatic view of apparatus and circuits showing a preferred form of the automatic regulating system of my invention arranged to adjust in a single step the voltage of a single-phase feeder circuit;

Fig. 2 is a diagrammatic reproduction of a portion of the system of Fig. 1 showing certain modifications in the booster-winding connections thereof;

Fig. 3 is a diagrammatic view of a modification of the improved regulating system of my invention which is adapted to provide two steps of circuit-voltage adjustment; and

Fig. 4 is a diagrammatic reproduction of a portion of the systems of Figs. 1 and 3 showing how the primary relay may be connected to respond to load current rather than to circuit voltage.

Referring to the drawing, and particularly to Fig. 1 thereof, the voltage-adjusting means of my invention are there diagrammatically represented as comprising a regulating transformer having a primary winding 12 adapted to receive energization from the voltage of a power-supply circuit 14—15 and a secondary winding 16—17 adapted to be connected in series with one of the conductors of a circuit 14—18 the voltage of which is to be regulated. Control of the portion of this secondary winding in this active connection is effected by a contactor 20 which, through a secondary relay 22, is controlled by a primary relay 24, the actuating winding 26 of which is energized by a measure of the voltage of supply circuit 14—15 derived from an auxiliary winding 28 associated with the main transformer.

As long as the supply-circuit voltage remains at or close to the desired value the several devices illustrated occupy the positions shown and power-circuit conductors 15 and 18 remain directly interconnected by member L of contactor 20. Under these circumstances the regulated circuit voltage is the same as that of the supply circuit 14—15.

When, however, the voltage of the supply circuit decreases to a predetermined value, for example, to 95% of normal, relay 24 engages a movable contact member 30 with a stationary member R', thereby completing for the actuating winding 32 of secondary relay 22, an energizing circuit which extends from the lower terminal of control supply winding 28 through conductor 34, relay contacts 30 and R', conductor 35, the relay

winding 32 and conductor 36, back to the upper terminal of control supply winding 28.

Thus actuated, secondary relay 22 moves, after a time delay which may vary from about ten to ninety seconds, a contact member 38 thereof upwardly, completing for the actuating winding 40 of the main contactor 20, an energizing circuit which extends from the lower terminal of control supply winding 28 through conductor 41, the winding 40, the relay contact 38, and conductors 42 and 36 back to the upper terminal of winding 28. Thus energized, the contactor 20 biases its contact members upwardly interrupting, by means of member L, the direct connection between circuit conductors 15 and 18 and establishing, by means of member R, a direct connection between the lower end of booster winding 16-17 and regulated circuit conductor 18.

Following the opening of contact member L and preceding the closing of member R, the power circuit current flows through a path which includes the upper section 16 of the booster winding and the winding 44 of a preventive auto transformer. The preventive auto 44 prevents an interruption in the circuit between the conductors 15 and 16 during operation of the contactor 20 from one circuit closing position to the other and serves as a reactor to prevent high circulating current through the local circuit supplied with voltage from the one or the other portions 16 or 17 of the secondary winding through the closed contact member L or R, thus preventing the short circuit current that would exist if the conductor 18 were directly connected to the midpoint between the secondary winding portions 16 and 17. By use of the arrangement shown, the tap-changing operation just described is made without interrupting the regulated-circuit current and the voltage impressed upon this circuit during the transition period is of a value intermediate that determined by the illustrated un-actuated position of the main contactor 20 and the described actuated position to which it is caused to move after persistence for a proper time of a primary relay control impulse.

This voltage-boosting adjustment of the equipment is maintained until the voltage of the supply circuit again increases to a certain value, for example, to 98% of normal, at which time the contacts 30 and R' of the primary relay 24 are caused to separate. A compounding coil 46 associated with this relay makes possible a separation of the contacts at a higher value of voltage than that which effected their original engagement. This disengagement deenergizes the actuating winding of secondary relay 22, allowing this relay, after a time delay similar to that previously mentioned, to move its contact member 38 downwardly, thereby interrupting the actuating circuit of the main contactor 20. The mentioned time delay feature afforded by relay 22 prevents unnecessary operations of the equipment by requiring that the change to be corrected uninterruptedly persist for a given time.

This allows the contact members thereof to again move downwardly to the illustrated position, member R interrupting the series connection of booster winding 16-17 between power circuit conductors 15 and 18 and member L re-establishing a direct connection between these two conductors. In this normal position of the several devices, the voltage of regulated circuit 14-18 is the same as that of supply circuit 14-15.

In practice, the magnitude of the voltage boost

for a single-step equipment is preferably of the order of from 5% to 10%. The connections of the secondary windings 16-17 shown in Fig. 1 provide a maximum value. In case it is desired to cut this value in half and at the same time to double the current carrying capacity of the equipment, this may be done by resorting to the parallel form of connection depicted in Fig. 2. It will be noted that in this connection, each of the winding sections 16 and 17 is provided with a mid-tap by means of which the corresponding halves of the two windings are connected in parallel circuit relation. A similar change is made in the interconnection of the two halves of the preventive auto-transformer winding 44.

In many situations, it is desirable to provide more than one step of voltage adjustment and for these the equipment depicted in Fig. 3 is particularly well suited. Basically, this system is the same as that of Fig. 1 with the exception that it is adapted to provide two steps of voltage adjustment. Associated with the booster windings 16-17 are two main or tap changing connectors 46 and 50 which through a pair of secondary relays 52 and 54 are controlled by the primary relay or contact making voltmeter 28' in accordance with deviations in the voltage of supply circuit 14-15.

In operation of the system of Fig. 3 when the supply circuit voltage is of the desired or normal value, the contact member 30 of the primary relay 24' occupies the disengaged or neutral position shown and both of the named main contactors occupy the illustrated unactuated positions. For such condition there is completed by means of contact member 56 and 58 carried by these contactors a circuit through which the upper section 16 of the transformer secondary winding is series-connected between power circuit conductors 15 and 18. Winding section 16 thus introduces into the regulated circuit an intermediate value of voltage boost.

In the event that the voltage of supply circuit 14-15 decreases to a predetermined value, for example, to 95% of normal, primary relay 24' engages contact members 30 and R', thereby competing for secondary relay 54 an actuating circuit which extends from the lower terminal of control supply winding 28, through conductor 34, contact members 30 and R' of relay 24', conductor 35, the winding 60 of secondary relay 54 and conductor 36 back to the upper terminal of control supply winding 28.

Thus energized, the relay 54 moves, after a predetermined time which may vary from ten to ninety seconds, its contact members 62 upwardly thereby completing for main contactor 48 an actuating circuit which extends from the lower terminal of control supply winding 28 through conductor 41, the actuating winding 64 of contactor 48, a switch blade 65, contact member 62 of secondary relay 54 and conductor 36 back to the upper terminal of control supply winding 28.

Thus energized, conductor 48 biases its contact members upwardly interrupting at member 56 the direct connection between the lower end of booster winding 16 and regulated circuit conductor 18 and establishing by means of member R'' a similar connection between the lower end of booster winding 17 and the same regulated circuit conductor. Following the opening of member 56 and preceding the closing of member R'', the power circuit current is carried by the preventive auto-transformer winding 44.

Upon completion of this described operation

both of the booster winding sections 16 and 17 are series connected between power circuit conductors 15 and 18 and the regulated circuit voltage is accordingly raised by the maximum amount. This condition maintains until the voltage of supply circuit 14-15 again raises to say 98% of its normal value at which time primary relay 24' biases its movable member 30 to the disengaged position illustrated thereby allowing, after a suitable time delay, secondary relay 52 to move to the unactuated position illustrated. This in turn restores the contact members of main contactor 48 to the positions shown in which only booster winding 16 is in active connection with the regulated circuit. The indicated difference between the contact engagement and disengagement voltage values of primary relay 24' is effected through the utilization of the compounding coils 46'.

In a similar manner, in the event that the voltage of supply circuit 14-15 rises to a predetermined value, for example to 105% of normal, primary relay 24' engages contact members 30 and L', thereby completing for secondary relay 52 an actuating circuit which extends from the lower terminal of control supply winding 28 through conductor 34, relay contact members 30 and L', conductor 66, the winding 68 of secondary relay 52 and conductors 69 and 36, back to the upper terminal of control supply winding 28.

Thus energized, relay 52 biases, after a predetermined time, its contact member 70 upwardly thereby completing for main contactor 50 an actuating circuit which extends from the lower terminal of control supply winding 28 through conductor 41, the actuating winding 72 of contactor 50, contact member 70 of relay 52 and conductors 73 and 36 back to the upper terminal of control supply winding 28.

Thus energized, this contactor biases its contact members upwardly, interrupting at member 58 the connections between the lower end of booster winding section 16 and regulated circuit conductor 18 and establishing by member L' a direct connection between supply source conductor 15 and the same regulated circuit conductor. By virtue of this direct connection the regulated circuit voltage is reduced to the same value as that of the supply circuit, no portion of the booster winding 16-17 then being in active circuit connection.

This low-voltage adjustment of the regulated circuit continues until the supply circuit voltage decreases to a certain value, for example to 102% of normal, at which time primary relay 24' separates contact members 30 and L', thereby allowing, after a time delay, secondary relay 52 to move to the unactuated position illustrated. As a result, main contactor 50 also moves to the unactuated position and restores booster winding section 16 into active connection with the regulated circuit. This introduces into the circuit the normal or intermediate value of boosting voltage.

When it is desired to by-pass the booster winding 16-17, as in taking the booster out of service, the switch, comprising blade 65 previously mentioned and a second blade 74, is thrown downwardly causing the booster to go to the non-boost position and stay there until the switch is again returned to the normal position illustrated. In the downward position blade 65 permanently opens the actuating circuit for voltage-raising contactor 48 and blade 74 completes the actuating circuit for voltage-decreasing contactor 50.

Instead of utilizing changes in supply circuit

voltage to actuate the primary relay, variations in the load current of the regulated circuit may also be employed. One preferred manner of effecting such modified control is indicated in Fig. 4 in which the actuating winding 26 of the primary relay 24' is connected with a current transformer 75 associated with the regulated circuit conductor 14. As the circuit loading increases, the primary relay is caused to bias contact member 30 downwardly into engagement with the contact member L', thereby effecting a corrective increase in the amount of boosting voltage. Similarly, when the circuit loading decreases below a given value, contact member 30 is biased upwardly into engagement with member R', thereby similarly effecting a corrective decrease in the magnitude of the boosting voltage.

Although I have shown and described certain specific embodiments of my invention, I am fully aware that many modifications thereof are possible. My invention, therefore, is not to be restricted except insofar as is necessitated by the prior art and by the scope of the appended claims.

I claim as my invention:

1. Voltage-adjusting means for an electrical circuit comprising a transformer having a secondary winding adapted to carry the circuit load current and a primary winding energized by the circuit voltage, a contactor having two circuit closing positions and adapted in one circuit closing position to connect said secondary winding in series-circuit relation with the circuit and in a second circuit closing position to interrupt and by-pass this connection, a primary relay, sensitive to changes in an electrical characteristic of the circuit, for controlling actuation of said contactor from one to the other of the two circuit closing positions above named, and an impedor adapted to carry the circuit load current during the period of contactor positional change and bypassed by said contactor in either of its circuit closing positions.

2. Voltage-adjusting means for an electrical circuit comprising a transformer having a secondary winding adapted to carry the circuit load current and a primary winding energized by the circuit voltage, a contactor adapted in one circuit closing position to connect said secondary winding in series-circuit relation with the circuit and in a second circuit closing position to interrupt and by-pass this connection, a primary relay, sensitive to changes in an electrical characteristic of the circuit, for controlling actuation of said contactor from one to the other of the two circuit closing positions above named, and a preventive auto-transformer winding bypassed by said contactor when in either of its circuit closing positions and adapted to carry the circuit load current during the period of contactor positional change from one to the other of its circuit closing positions.

3. A voltage-controlling regulator for an electrical circuit comprising a transformer having a secondary winding and a primary winding energizably connected across the circuit, a contactor adapted in one position to connect said secondary winding in series-circuit relation with the circuit and in a second position to interrupt and by-pass this connection, a preventive auto-transformer winding permanently interconnect ed between said secondary winding and the regulated circuit to carry the circuit load current only during the period of contactor positional change from one to the other of the two above-named positions, and a primary relay, sensitive

to changes in an electrical characteristic of the circuit, for controlling actuation of said contactor from one to the other of the two above-named positions.

- 5 4. A voltage-controlling regulator for an electrical circuit comprising a transformer having a secondary winding and a primary winding energizably connected across the circuit, a contactor having two circuit closing positions and adapted in one circuit closing position to connect said secondary winding in series-circuit relation with the circuit and in the other circuit closing position to interrupt and by-pass this connection, a preventive auto-transformer winding connected between an intermediate point along said secondary winding and the regulated circuit in such manner that it carries, through a portion of said secondary winding, the circuit load current only during the period of contactor 10 positional change from one circuit closing position to the other circuit closing position, and a primary relay, for controlling actuation of said contactor from one to the other of the two above-named positions.
- 15 5. Voltage-adjusting means for an electrical circuit comprising a transformer having a primary winding energized by the circuit voltage and a secondary winding having two series-connected sections the end of one of which is connected with one of the conductors of the power-source side of the circuit, a preventive auto-transformer winding connected between the other end of said secondary winding section and the corresponding conductor of the regulated side of the circuit thereby placing the two windings last named in series-circuit connective relation with said circuit, a contactor adapted to shunt said connection, a second contactor adapted to connect the free end of the other of said 20 secondary winding sections with the regulated circuit conductor above named, and a primary relay, sensitive to changes in an electrical characteristic of the circuit, for selectively controlling actuation of said two contactors.
- 25 6. Voltage-adjusting means for an electrical circuit comprising a transformer having a primary winding energized by the circuit voltage and a secondary winding having two series-connected sections the end of one of which is connected with one of the conductors of the power-source side of the circuit, a preventive auto-transformer winding connected between the other end of said secondary winding section and the corresponding conductor of the regulated side of the circuit thereby placing the two windings last named in series-circuit connective relation with said circuit, a contactor adapted to shunt 30 said connection, a second contactor adapted to

connect the free end of the other of said secondary winding sections with the regulated circuit conductors above named, means whereby an occupation of the unactuated position by both contactors establishes a shunt connection around said preventive auto-transformer winding, and a primary relay, sensitive to changes in an electrical characteristic of the circuit, for selectively controlling actuation of said two contactors.

5 7. A voltage-controlling regulator for an electrical circuit comprising a transformer having a secondary winding and a primary winding energizably connected across the circuit, a switch adapted in one position to connect said secondary winding in series circuit relation with the circuit and in a second position to interrupt this connection and bypass said secondary winding, a primary relay sensitive to changes in an electrical characteristic of the circuit for controlling actuation of said switch from one to the other 10 of the two above named positions, and means for rendering said relay sensitive in differing degrees to the rising and falling directions of change in the regulated characteristic.

15 8. A voltage-controlling regulator for an electrical circuit comprising a transformer having a secondary winding and a primary winding energizably connected across the circuit, a two-position electro-magnetically operated contactor adapted in its actuated position to connect said secondary winding in series circuit relation with the circuit and in its deactuated position to interrupt this connection and bypass said secondary winding, a primary relay sensitive to changes in an electrical characteristic of the circuit for controlling 20 actuation of said contactor from one to the other of the two above named positions, and means for rendering said relay sensitive in differing degrees to the rising and falling directions of change in the regulated characteristic.

25 9. A voltage-controlling regulator for an electrical circuit comprising a transformer having a secondary winding and a primary winding energizably connected across the circuit, a switch adapted in one position to connect said secondary winding in series circuit relation with the circuit and in a second position to interrupt this connection and bypass said secondary winding, a normally substantially non-current carrying inductive winding connected between an intermediate point along said secondary winding and the regulated circuit in such manner that it carries through a portion of said secondary winding the circuit load current during the period of switch 30 positional change, and a primary relay for controlling actuation of said switch from one to the other of the two above named positions.

FRANKLIN I. SNYDEF
